FRITZ SCHRÖTER, OF BERLIN, GERMANY, ASSIGNOR TO TELEFUNKEN GESELLSCHAFT
FÜR DRAHTLOSE TELEGRAPHIE M. B. H., OF BERLIN, GERMANY, A CORPORATION
OF GERMANY

HIGH SPEED TELEGRAPHY SYSTEM

Application filed June 11, 1929, Serial No. 370,092, and in Germany June 8, 1928.

The present invention is concerned with a high-speed telegraph apparatus predicated for its operation upon the use of conversion means of the kind employed in picture transmission. Insofar as its fundamental features are concerned, this apparatus can be used both for wire lines as well as for radio, although, essentially, it is particularly suited for short-wave operation. To change the 10 telegraphic signals into impulses of current, a photo-electric cell (selenium cell, selenium-tellurium cell, potassium photo-electric cell, etc.) is employed at the sending end. To re-convert the incoming current impulses into 15 signals one of the well-known inertialess light relays is used in case of photographic recording, say, a glow-lamp or a Kerr cell, while in case of electrochemical recording, means as likewise known from electrolytic 20 picture telegraphy (production of electrochemical color reactions upon specially sensitized or prepared paper) are employed.

In short-wave high-speed telegraphy, safe operations have heretofore been impeded 25 mainly on account of the fading of the incoming signal and further because of atmospherics. To remedy this condition various ways and means have been suggested: such as, (1) electric expediencies to the end of 30 diminishing fading and to keep the signal strength at a constant value by periodical variation of the wave-length, by the aggregation of several receiving antennæ and by amplitude-limiting amplifiers, and (2) sev- 35 eral repetitions of each signal or signal element at certain time intervals and combination or aggregation of several equi-directional receiving signals to result in an ultimate recorded signal as a means to filter 40 out or separate disturbances or strays, which have acted like signals.

For printing telegraphs, as for example, by the Baudot systems, it has been previously suggested to repeat each element or 45 constituent of a signal (or sign) combination at intervals and to cause a chain of contacts to be closed by the different impulses corresponding to it, the printing current proper being caused to flow only through 50 the agency of said contacts (Verdan principle).

However, devices of this nature involving mechanically moved contacts and printing means and their distributors have a good deal of inertia whereby the rate of speed of the transmission is limited. The 55 said electrical means provided to combat signal fading involve a number of drawbacks, chiefly inherent in that they raise amplification rather strongly whenever the signal strength falls off, and that incidentally also the stray level, as it were, is correspondingly raised, with the consequence that 60 initiation or masking of the incoming signal is liable to happen.

The invention has recourse to the principle of signal repetition in the form of inertialess conversion practically free from limiting the transmission rate, and of the combination or aggregation of constituent records to form the ultimate signal, and this 65 in a form which insures proper selection even in a case when one or several of the elementary impulses have been skipped or have dropped out during fading intervals. By virtue of the high safety of signal selection 70 thus attained, and the high transmission speed thus insured, it is feasible to obtain mechanical translation free from errors of the symbolic telegraphic messages into open (or decoded) letters separately from the 75 long-distance transmission itself in a distinct working process at the receiving place, in a way as shall be shown by what follows further below. It is thus also possible to run several such translator apparatus in parallel 80 in order that the volume of messages coming in through the channel of the long-distance transmission may be handled without accumulation and be passed on.

The invention shall be here described in 85 adaptation to the so-called five-unit alphabet or code in which, in well-known manner, the signal is formed and built up by a combination of a maximum of five elements or units. However, the idea underlying this 90 invention is applicable also to other kinds of symbolic telegraph signals, say, the Morse code.

Other objects and advantages will herein- 95 after appear from a reading of the following 100

specification and claims in connection with the accompanying drawings, wherein:

Fig. 1 schematically illustrates the transmitting principle;

Fig. 2 diagrammatically illustrates one form of transmitting apparatus;

Fig. 3 diagrammatically illustrates a suitable form of receiving apparatus;

Fig. 4 shows a glow-lamp suitable for recording received signals;

Fig. 5 illustrates a development of the diaphragm shown in connection with the receiving apparatus of Fig. 3;

Figs. 6 and 7 illustrate two forms of received records; and

Fig. 8 illustrates a further modification of the system shown by Figs. 2 and 3.

Referring to Fig. 1, 1 is an intermittently, or preferably, continuously travelling telegraphic tape or band which is provided along both margins with perforations to insure better guiding. The signals are punched therein or printed thereon in five-unit combinations, according to whether transparency or reflection is used as the underlying principle of photo-electric scanning, as customary in picture telegraphy. As shown in Fig. 1, the constituent elements of each telegraphic signal, for example, have the form of elongated, narrow slits to allow light to pass therethrough, these slits being arranged superposed in five rows 6, 7, 8, 9, 10, and being caused to travel past light-passage or illuminating slits 2, 3, 4, or 5.

The telegraphic tape should for this object consist most suitably of opaque paper. What is essential is the oblique disposition of the different corresponding elements, the latter being at such an interval from one another, measured in the direction of travel of the strip, that between the passages of two consecutive elements of the signal in front of one and the same light-passage slit, there is provided sufficient time in order that elements of other signals at other such slits may be allowed to act alternately.

In this manner, at a given instant, light will be allowed to pass through a single element to the photo-electric cell, i. e., alternately at slit 2, 3, 4 or 5, to which are coordinated four adjustable sections 11, 12, 13 and 14 of the telegraph strip 1 separated by intervals chosen at will. The operation of such an optical transmitter strip can be followed most clearly from the drawing by starting from that element of cell 8 which happens to be located in the rear of slit 2 (section 11). At that instant, no light will be permitted to fall through slits 3, 4, 5, upon the transmitter cell. Now, as the tape continues to travel in the direction of the arrow, it is first the element of row 8 which pertains to the signal scanned in section 12 that comes to be positioned in the rear of slits 3, while all of the other slits are covered.

The next light scanning takes place in section 13 by that an element in the slit row 8 moves in the rear of slit 4, while at the same time all of the other slits are covered up.

When line 8 at slit 5 is finished, the scanning of the elements of row 9 begins, if these exist at all. In this manner operations proceed by that (1) at any given instant only one element is being transmitted, and (2) that each element for n light-passage slits, is transmitted n times at conveniently pre-arranged time intervals. The selection of four slits as here mentioned is merely by way of example, indeed, the number thereof can be chosen either smaller or larger, according to service requirements.

One exemplification of the optical outfit for the photo-electric scanning of the transmitter strip or tape according to the principle underlying Fig. 1 is shown in Fig. 2. The tape is here denoted by 25 and the same is caused to travel continuously past the slits 2, 3, 4, 5 formed or recessed in the cylindrical wall of the housing 15. Snug contact of the tape is insured by guiding the latter over rolls or pulleys. These rolls denoted by 26, 27, 28 are finely adjustable and allow of a delicate adjustment of the distance between the different scanning zones. In front of the slits 2, 3, 4, 5, glow-lamps equipped with filaments 21, 22, 23, 24, are mounted, the latter most preferably being disposed at one side and having the shape of spirals or bands in order that the real source of luminosity may be positioned as closely as possible to the slits in the transmitter strip and the passage-slit. The light falling therethrough is thrown by the agency of lenses 16, 17, 18 and 19 upon the photo-electric cell 20, say, a potassium type of photo-electric cell, such as an Elster and Geitel cell, whereby the current impulses controlling the transmitter are generated. In case of reflection scanning instead of the scanning here suggested, the arrangement must be modified correspondingly, as is fundamentally known from picture telegraphy.

Fig. 3 illustrates means for receiving by the aid of photographic recording upon a band of photographic paper similar to the transmitter strip being guided by the aid of marginal perforation. This band 48, similarly to the arrangement shown for the transmitter apparatus, Fig. 2, is guided over pulleys or rollers, and is passed opposite the illuminating slits 37, 38, 39 and 40 which are indicated also in Fig. 5. Through these slits, from the inertialess receiver light source, 29, 30, 31, mounted in the interior of the housing or case, photographically active light is thrown upon the recording strip through the lenses 32, 33, 34, 35. Each light source is controlled by the incoming

currents in a way as is well known from picture telegraphy.

It is suitable to employ a glow-discharge lamp having a markedly actinic gas-filling, such as a mixture of argon and nitrogen, or other appropriate and known gases. However, the ultraviolet spectrum may be utilized by that the container of the lamp and also the lenses are manufactured from uviol glass, quartz or the like permitting the transmission of such rays.

The construction of a lamp useful for this purpose is shown, though only schematically, in Fig. 4, without it being intended to show dimensional relations and details of the arrangement. In the interior of the lamp bulb 29 there are two electrodes, one thereof being the glow-light (glow-discharge) cathode 30 having the form of part of a cylinder and being insulated against the starting of glow-discharge currents upon the inner side thereof, while the other one is the anode 31 surrounding the former "clip or bow" fashion. It is not necessary in this place to furnish further details of this luminous source, its connection and control. What is only essential here is that the cathode sheet 30 is closed to form a cylinder to such an extent that, looked at from the various directions of the image-producing lenses 32-35, it presents the same surface size in order that the images thrown upon the different light-passage slits 41-44, Fig. 3, may turn out to be of equal size. Of course, it is also possible to use conveniently designed Kerr cells or other light valves in lieu of the glow-discharge tube.

Rolls or pulleys 45, 46, 47 serve the same purpose as the rolls 26-28, Fig. 2. There is further provided a rotating diaphragm 36 which exposes always only one of the slits 41-44, and of these only a part in the direction of its height corresponding to lines 6-10, so that each light impulse of the glow-discharge lamp 29 produces a blackening effect only on a very definite portion of the recording strip coordinated to an element. Of the light-passage openings of the diaphragm 36, only four are shown, 37-40, Fig. 3, for the sake of greater clearness of illustration, to illustrate the change in illumination inside the sections which correspond to the slits 41-44.

The actual disposition of the arrangement can be seen more lucidly from Fig. 5 showing part of the development of the diaphragm 36. For the sake of clearer understanding, the stationary slits 41-44 have only the interval of a single signal, while in reality, measured upon the strip, they may be chosen any desired multiple thereof as indicated in Fig. 1. It can again be seen from Fig. 5 that light is permitted to fall momentarily only through a single slit, and that the slits alternate in reception in the

very same way as at the sending end. In this manner, working conditions are made so that the four (or n many) individual or elementary impulses which each signal is sending out, is recorded and combined in an integrating manner at the same point of the receiving strip, provided that the transmitter and receiver tapes as well as the diaphragm 36 are running in synchronism. If the blackened portions for each element are not to be combined or aggregated at one and the same place of the receiving strip by exact registering of the n many marks, then it is also possible to operate in such a way that the constituent marks which transmit the element in question at intervals, are alined band-fashion; but in that case it is the blackened area rather than the degree of blackening that is evaluated in the translation to be described further below. This modification in the scheme is possible by that the illuminating slits are staggered or displaced by stages by the width of an element with reference to the position to be shown in Fig. 5. The markings will then not cover one another, but rather will be alined.

This latter mode of operation allows of a very accurate signal "selection" if operations are so that each individual impulse will cause blackening in the photographic layer until the point of saturation is reached. While the incoming signals upon a strip which has been recorded according to the method of aggregation or summation of blackening action have an appearance as shown in Fig. 6 (pictures 49 of the slits of sending tape, Fig. 1), a receiving strip based upon summation of areas according to the last-named method is illustrated in Fig. 7, where 50 denotes the surfaces resulting from the alining of constituent images of the slits of the transmitter strip.

Diaphragm 36 (Fig. 3) must work in analogy with the transmitter strip, i. e., continuously, if the latter runs also nonintermittently. But if it works intermittently, then means must be provided also at the receiving end for the object of insuring intermittent change of slit and strip conveyance.

Instead of an arrangement as shown in Fig. 3, it would be feasible to use an equipment operating with as many inertialess light sources as there are illumination slits, and in which the different light sources (glow-discharge tubes, Kerr cells, etc.) are commutated by the agency of a synchronous switch. All that is then necessary is, most suitably by the aid of a suitably moved diaphragm, to limit the height or length of the marks in conformity with lines 6, 7, 8, 9, 10 and to alternate the lines themselves at the proper sequence.

If electrochemical recording of signals is resorted to in lieu of photographic recep-

tion, the outfit shown in Fig. 3 is replaced by an arrangement wherein proper position of the chemical marks upon the receiving tape is insured by alternating commutated (changed over) contacts for the passage of the current, these contacts taking here the place of the slits provided for the passage of the light.

Translation of the signal received by an equipment as hereinbefore described into printed letters may be most suitably insured by the same outfit as used with the Siemens high-speed telegraph, in the Baudot multi-channel (multiplex) telegraph or other systems for converting the current impulse combination into types of the standard alphabet. The current impulses required for the actuation of the translator, of course, are not produced by contact-makers fed with perforated strips as customary in the above types of apparatus, but rather by the aid of a photo-electric exploring or scanning device which takes here the place of the said contact makers at the transmitting end.

The photo-electrically actuated translator device will vary according to whether the covering or the alining (or surface aggregation) method is used on the photographic receiving tape. The common basic principle is that, to eliminate stray, the translator element is caused to respond and operate whenever a certain and sufficient number of constituent impulses for each element has been recorded. For instance, if each element is transmitted six times, the proper thing probably is to so choose the responding threshold that a blackening intensity or a blackening area corresponding to the action of three recorded impulses, will result in the minimum value required for the response of the translator element. This, on the one hand, insures adequate selectance with reference to disturbances and stray inasmuch as the likelihood that stray will systematically again and again fall with sufficient intensity inside the short time interval of the recording of the element in question, is small enough in order that under practical conditions all chances may be precluded of three stray signals being recorded at a place instead of genuine telegraphic impulses.

On the other hand, the correct control of the translator is still possible in this scheme whenever three of the six individual impulses that have been sent out have failed to arrive owing to fading. According to prevailing working conditions, of course, the number of constituent impulses per element and the threshold value for the photo-electric actuation of the translator apparatus (with the necessary tolerances) will have to be chosen different.

In order to insure translation in the telegraphing method according to the invention, the receiving strip (which may be divided

between a more or less great number of apparatus) is caused to travel past an exploring device which consecutively causes the different elements of the signal combination to act upon the photo-electric cell. The threshold of response can be adjusted, e. g., by convenient "grid potential blocking" of the amplifier amplifying the photo-electric current, irrespective of whether the degree or the area of blackening is evaluated. The current impulses produced by the photo-electric cell then adjust and operate, in known manner, the relays of an ordinary translator device of the kind as found complete in present day equipments, for instance, in the Baudot or Siemens telegraphs. Between the scanning device for the translation and the translator controlling the printing means, of course, there may be a more or less long line over which the telegram coming in on a short wave may be reforwarded.

Fig. 8 diagrammatically shows an exemplification for local translation of the photographic or electrochemical receiver strip or tape according to Figs. 6 or 7 into a series of open letters. The strip that is to be translated is designated by 48 and it travels over pulleys 49, 50, and past a photo-electric scanning or exploring device. The light issuing from a luminous source (glow-lamp) 53 is thrown through a rotating diaphragm 54 (on which only a part of the breaks or perforations 55 is shown) by the aid of a lens 52 upon the tape 48, at a rate or rhythm so that consecutively the constituent elements of a signal are brought to be photo-electrically evaluated according to the principles hereinbefore set forth. Inasmuch as the scheme is based upon the reflection of light, the photo-electric cell (selenium, selenium-tellurium or photo-electric cell) which is denoted by 51 is most suitably made of annular shape in order that a maximum part of the reflected light may be utilized. The current impulses produced by this cell and amplified by amplifier 61 in well-known manner are brought to act upon the relay 62, 63 which takes the place of the standard receiving relay of a Siemens or Baudot type printing telegraph apparatus.

Otherwise, the translator device of standard type of this system is used in a practically unaltered manner. The same is designated by 59, and is here indicated merely schematically. By the relay 63 the five selector relays are actuated in the usual manner, and the adjustment combinations of the same result during the printing process in the selected letters upon the tape 60. It goes without saying that the speed of rotation of the diaphragm 55, the speed of translation of the tape 48, and the speed of the type selector in the translator 59 must bear a certain relationship to one another.

For this purpose, all of these actions are made dependent upon the same motor 57 which, by the agency of a transmission gear 58 and the like mechanical coupling 56 governs the relationship of the speeds.

Having now described my invention, what I claim and desire to secure by Letters Patent is the following:—

1. In a high speed telegraphy system, the method of transmission which comprises repeatedly transmitting each element of each signal at time separated intervals, and receiving and independently recording as received each signal to produce the sum total of the separately transmitted impulses for each of the transmitted elements.

2. In a high speed telegraphy system, the method of transmission which comprises repeatedly transmitting each element of each signal at time separated intervals, receiving and independently recording all received signals for evaluating the sum total of the separately transmitted signal impulses for each of the transmitted elements, and controlling from the evaluated impulses a translator apparatus for reproducing the signal combinations into open signals.

3. In a high speed signalling system, the method of transmission which comprises repeatedly transmitting each element of each signal at time separated intervals, recording each of the signals on a recording tape divided into a number of sections, and utilizing each of the sections for controlling a translating device for evaluating the sum total of the separately transmitted elements corresponding to each of the signals.

4. In a high speed telegraphy system, the method of transmission which comprises grouping each of the elements corresponding to the transmitted signals into a plurality of rows arranged obliquely and positioned with predetermined separation with respect to each other on a record tape, transmitting the signals from the record tape so that each element of each signal is transmitted a plurality of times at time separated intervals, and receiving and evaluating the sum total of the received signals so as to form a received record corresponding to the sum total of the transmitted signal impulses.

5. In a high speed telegraphy system, the method of transmission which comprises grouping each of the elements corresponding to the transmitted signals into a plurality of rows arranged obliquely and positioned with predetermined separation with respect to each other on a record tape, transmitting the signals from the record tape so that each element of each signal is transmitted independently of each other signal a plurality of times at time separated intervals and receiving and evaluating the sum total of the received signals so as to form a received record corresponding to the sum total of the

plurality of independently transmitted signal impulses.

6. In a high speed telegraphy system, a record tape having the signals for transmission arranged thereon in a plurality of rows arranged in staggered position with respect to each other, a light converting element for converting the signals into electric current impulses, and means for passing the record tape before said light converting element so that each portion of the said record tape is adapted to influence the said light converting element at time separated intervals and so that each portion of the record tape will produce from said light converting element a plurality of time separated impulses separate from the impulses produced by each other portion of the record tape.

7. In a high speed telegraphy system, a record tape having a plurality of markings thereon representing a message for transmission, said markings being arranged in a plurality of parallel rows and separated with respect to each other by predetermined separations, a light converting element, a diaphragm for screening said light converting element from said record tape, and means for passing said record tape relative to said light converting element and said diaphragm so that each element on the said record tape separately influences the said light converting element a plurality of times whereby electrical impulses corresponding to the transmitted signals are generated in the light converting element.

8. In a high speed telegraphy system, means for transmitting each element of a series of signals a plurality of times at time separated intervals, means for receiving the transmitted signals, and means for independently recording the received signals in predetermined positions so that the separately transmitted time separated impulses corresponding to each of the separate signals produce an aggregate record corresponding to the single transmitted record.

9. In a high speed telegraphy system, means for transmitting each element of a record a plurality of times at time separated intervals, means for receiving the time separated signals corresponding to each element of the transmitted record, means for producing light impulses from the received signals, means for passing a recording surface relative to the source of production of said light impulses so that the light produced influences the recording surface, and a diaphragm positioned between said recording surface and said light producing means for controlling the position on the recording surface at which the generated light influences the same, whereby the time separated signalling impulses produce on the recording surface an evaluated record.

corresponding to the aggregate of the said separately transmitted signalling impulses.

10. In a high speed telegraphy system, means for transmitting each element of a record independently of each other element a plurality of times at time separated intervals, means for receiving all of the time separated signals corresponding to each independent element of the transmitted record, means for controlling a record producing means from the received signals, means for passing a signal recording surface relative to the said record producing means, and a diaphragm positioned between said recording surface and said record producing means for controlling the position on the recording surface at which the record producing means may influence the recording surface, whereby the time separated signalling impulses produce on the recording surface an evaluated record corresponding to the aggregate of the said independent and separately transmitted signalling impulses.
15. In a high speed telegraphy system, means for transmitting each element of a signal a plurality of times at time separated intervals, means for receiving the transmitted signals, an inertialess light source controlled from said received signalling impulses, a recording tape adapted to be influenced by the light generated in said light source, and a diaphragm positioned between said light source and said recording tape for controlling the position on said recording tape at which the generated light impulses are effective, whereby the plurality of time separated signals as transmitted are evaluated into a composite record having a density corresponding to the aggregate of all of the transmitted impulses.

20. In a high speed telegraphy system, a five unit record tape having markings, corresponding to signals for transmission, placed thereon, means for converting each of the markings on the record tape into a plurality of time separated electrical impulses, means for receiving the time separated electrical impulses produced from the record tape, means for utilizing said received electrical impulses for producing light values corresponding to the received signals, a recording tape, and means associated with the recording tape for varying the position of markings produced thereon by said generated light, whereby the separated signalling impulses produce a plurality of markings on the record tape appropriately coordinated to a single area thereof.

25. In a high speed telegraphy system, a five unit record tape having markings, corresponding to signals for transmission, placed thereon, means for converting each of the separate markings on the record tape

into a plurality of time separated electrical impulses independent of the impulses produced from each other marking, means for receiving the time separated electrical impulses produced from the record tape, means for utilizing said received electrical impulses for producing light values corresponding to the received signals, a recording tape, and a diaphragm associated with the recording tape for varying the position of markings produced thereon by said generated light, whereby the separated and independent signalling impulses produce on the record tape an evaluated record corresponding to the sum total of all of the signalling impulses corresponding to a single area of the transmitted record.

14. In a high speed telegraphy system wherein each signal is transmitted a plurality of times with a time separation between successive transmissions, a receiving means comprising means responsive to the time separated signals corresponding to the record transmitted for producing light values proportionate to the received signals, a record tape for recording the light values representing signals corresponding to the markings on the record surface for transmission, and a diaphragm associated with the recording tape for varying the position at which the record tape is subjected to the light values produced by received signals, whereby the separated and independent signalling impulses produce on the record tape an evaluated record corresponding to the sum total of all of the signalling impulses corresponding to a single area of the transmitted record.
